IRA S. MOSHER, OF DETROIT, MICHIGAN

INTERNAL COMBUSTION ENGINE

Application filed May 13, 1930. Serial No. 451,907.

The invention relates to internal combustion engines and among its objects are the following: to provide an improved structure of engine for increasing the power of same without adding materially to the weight thereof; to provide an engine in which greater flexibility may be obtained both in traffic and general road work; to eliminate all side thrust of the pistons ordinarily caused by the connecting rods; to cause power impulses to occur during the entire 360° of crank movement instead of only 180° as in the conventional motor; to provide a motor which will develop its rated horse power at low speed, thus having all the advantages of an opposed cylinder motor with none of its disadvantages; and to provide a motor in which compression takes place under a power impulse and not on an idling stroke as in ordinary motors.

The invention contemplates the use of an opposed cylinder motor. Ordinarily in motors of this type the pistons are connected to each other or to cranks connected to the crank shaft. This necessitates the use of stuffing boxes or other more or less complicated structures which are highly impractical in the present day high speed engine. In accordance with the present invention the pistons are connected with sliding cross-heads which, although independent of each other, always move in unison. One of the sliding cross-heads is connected to the crankshaft and numerous advantages accrue from this construction and will be explained in detail hereinafter.

Other advantages and objects than those heretofore mentioned will become apparent as this specification proceeds and still others will be obvious without being pointed out and described in detail.

For a proper understanding of the invention drawings have been provided in which similar characters of reference indicate corresponding parts in all the views. Referring to said drawings:

Fig. 1 is a longitudinal sectional view, parts being in elevation;

Fig. 2 is a fragmentary detail sectional view taken on line 2-2 of Fig. 1; and

Figs. 3 and 4 are a front elevation and side elevation, respectively, of the lower sliding cross-head.

Referring again to said drawings the reference numeral 5 designates generally the upper cylinder block and 6 the lower cylinder block. Each cylinder block may contain as many cylinders as desired; for instance if each block contained six cylinders a vertical twin six engine would be provided. As the longitudinal sectional views through any pair of cylinders would be alike except for the different positions of the pistons which would depend upon the timing of the motor it is thought the showing made in Figs. 1 and 2 will suffice for an engine containing any desired number of pairs of opposed cylinders. The terms upper and lower as they appear in the specification and claims are to be understood as simply terms of orientation as it would be quite feasible to set the engine up in various positions.

It will also be understood that any parts mentioned hereinafter in the singular are to be construed as referring to all such similar parts in the motor.

The cylinders in the upper block are designated by the numeral 7 and those in the lower block by the numeral 8. These cylinders are open at their extreme ends and at their adjoining ends are provided with cylinder heads 9 and 10 having offset combustion chambers 11 and 12. The cylinder heads are secured in place by set screws 13 and are secured together by set screws 14. The set screws 14 are easily accessible so that the engine may be taken down with little trouble. The usual spark plugs 15 and 16 are provided and valves 17 and 18. The valves 17 and 18 are the intake valves and it is understood the exhaust valves are directly behind them, the valve stem of one of the exhaust valves being indicated at 19 in Fig. 2. The intake manifold is designated generally by the reference character 20.

Upper and lower pistons 21 and 22 are provided in the cylinders 7 and 8. Due to the fact that means, hereinafter described, are provided for eliminating the side thrust on the pistons they may be made consider-

ably shorter and lighter which, as is well known, has numerous advantages in the modern high speed engine, not thought necessary to dwell on at the present time.

5   Mounted in guides 25 and 26 adjacent to and in close proximity with the cylinders are upper and lower cross-heads 27 and 28. The guides 27 and 28 may be made separate from the cylinder blocks and secured thereto in any desired manner or they may be integral 10 with the cylinder block as illustrated in the drawings. The cross-heads 27 and 28 are considered an important feature of the present invention. They are preferably of skeleton construction so as to be light in weight 15 and their wearing faces may be of hardened steel. The lower cross-head is connected by the connecting rod 29 to the crank shaft 30. Thus the lower cross-head will take all the side thrust imparted by the connecting rod 29. The long bearing surface and construction 20 of the cross-heads enable them to stand a great deal of wear and even if a small amount of lost motion develops there will be very little harm done in comparison to this 25 happening to the piston. The cross-heads are easily accessible and may be renewed with very little trouble and slight expense. The upper cross-head might be the same as the lower one but due to the fact that it has considerably less work to do and less strain it 30 is preferred to make it lighter as illustrated.

It is preferred to make the cross-heads 27 and 28 separate and connect them together 35 by the straight line link 31. If a single integral cross-head were used the cylinder blocks would have to be lined up with absolute accuracy. Even a few thousandths deviation would cause a terrible strain on the 40 parts and probably result in permanent injury or disaster. While it is desired to have as much accuracy as possible used the connecting link 31 would allow for any slight discrepancies.

45   The cross-heads are provided with lateral extensions 35 and 36. Pivoted at 37 to the extension 35 is a link 38 which in turn is connected by the wrist pin 39 to the piston 21 in the upper cylinder 7. Pivoted at 40 to the extension 36 is a similar link 41 connected by the wrist pin 42 to the piston 22 in lower cylinder 8. By virtue of the lateral extensions 35 and 36 from the cross-heads and the vertical movement of the cross-heads a 50 straight line motion is imparted to the pistons by the links 38 and 41, thus eliminating all side thrust on the pistons.

55   It will be noted that the pistons are so arranged that on the power stroke of one piston the opposite piston is compressing instead of idling. For instance, in Fig. 1 the piston in the lower cylinder is in the firing position or at the beginning of the power stroke and the piston in the upper cylinder 60 is at the beginning of its compression stroke.

Thus in a twin six motor we would obtain six impulses, 60° apart, for one revolution of the crank shaft. However the timing may be varied. The cylinders in the top cylinder block may be timed to get their compression 70 under power from the cylinders in the lower cylinder block or the timing may be directly opposite so as to allow the cylinders in the lower cylinder block to compress under power stroke from the cylinders in the upper block. 75 Another possibility would be to time it so as to compress under power, alternately, upper and lower. However the arrangement of compressing in the upper cylinders under a power stroke from the lower cylinders is thought to be best as it distributes the power 80 in a much more uniform manner.

85   The arrangement and operation of the valves and the timing may be done in any approved manner. By way of example the valve stems 45 or their tappets are engaged by cams 46 on cam shafts 47. The lower cam shaft 47 has a gear 48 mounted thereon. A gear 49 is mounted on the crank shaft and sprocket chain 50 engages gears 48 and 49, idle gear 51 and gear 52. Mounted on the same shaft as gear 52 is a helical gear 53. This helical gear 53 engages another helical gear 54 secured to shaft 55. The upper end of shaft 55 carries another helical gear 56 which meshes a helical gear 57 on the upper cam shaft 47. In this manner the valves are all 90 operated in proper relation to the crank shaft. The arrangement and operation of the valves forms no specific part of the present invention and may be widely varied.

95   Numerous changes may be made in details of construction and arrangements of parts by one skilled in the art without departing from the spirit of the invention or the scope of the appended claims.

I claim:

1. An internal combustion engine having in combination, pairs of opposed cylinders, pistons mounted independently of each other and adapted to move in unison with each other in said cylinders, upper and lower cross-heads for each pair of cylinders, said cross-heads of each pair being linked together and mounted for reciprocal movement adjacent said cylinders, connections between said cross-heads and said pistons, and connections between said cross-heads and the crank shaft of said engine.

110   2. An internal combustion engine having in combination, pairs of opposed cylinders, each pair comprising an upper and lower cylinder, pistons in said cylinders, upper cross-heads, lower cross-heads, links connecting said upper cross-heads to the pistons in said upper cylinders, links connecting said lower cross-heads to the pistons in said lower cylinders, links connecting said upper and lower cross-heads, guides adjacent said cylinders.

ders for said cross-heads, and connections between said lower cross-heads and the crank shaft of said engine.

3. An internal combustion engine having in combination, pairs of opposed cylinders, each pair comprising an upper and lower cylinder, pistons in said cylinders, upper cross-heads, lateral extensions on said upper cross-heads, links connecting said lateral extensions to the pistons in said upper cylinders, lower cross-heads, lateral extensions on said lower cross-heads, links connecting said lateral extensions to the pistons in said lower cylinders, links connecting said upper and lower cross-heads, guides adjacent to and in close proximity with said cylinders for said cross-heads, and connections between said lower cross-heads and the crank shaft of said engine.

20 4. An internal combustion engine having in combination, pairs of opposed cylinders, each pair comprising an upper and lower cylinder, pistons arranged in said cylinders so that compression takes place in one cylinder under a power stroke in its opposing cylinder, upper and lower cross-heads, guides adjacent said cylinders for said cross-heads, connections between said upper and lower cross-heads and the pistons in said upper and lower cylinders whereby side thrust of said pistons in said cylinders is eliminated, straight line connections between said cross heads, and connections between said lower cross-heads and the crank shaft of said engine.

In testimony whereof I affix my signature.
IRA S. MOSHER.
